US0D1058521S

(12) **United States Design Patent** (10) **Patent No.:** **US D1,058,521 S**
(45) **Date of Patent:** **** Jan. 21, 2025**

(54) **DIGITAL POWER SWITCH**

(71) Applicant: **XiaMen YiDongsheng Technologies Co Ltd**, Xiamen (CN)

(72) Inventor: **Zhiqin Fang**, Xiamen (CN)

(73) Assignee: **XiaMen YiDongsheng Technologies Co Ltd**, Xiamen (CN)

(**) Term: **15 Years**

(21) Appl. No.: **29/948,778**

(22) Filed: **Jun. 24, 2024**

(51) LOC (15) Cl. **13-03**

(52) U.S. Cl.

USPC **D13/158**

(57) **CLAIM**

The ornamental design for a digital power switch, as shown and described.

DESCRIPTION

FIG. 1 is a front, top and right perspective view of a digital power switch showing my new design;

FIG. 2 is a rear, bottom and left perspective view thereof; FIG. 3 is a front view thereof, a rear view being a mirror image of the front view;

FIG. 4 is a left side view thereof, a right side view being a mirror image of the left side view;

FIG. 5 is a top view thereof;

FIG. 6 is a top view thereof, shown in a digital display state;

FIG. 7 is a bottom view thereof; and,

FIG. 8 is an exploded view thereof.

The broken lines depict portions of the digital power switch that form no part of the claimed design.

1 Claim, 8 Drawing Sheets
